Attorney.

UNITED STATES PATENT OFFICE.

JAMES M. BERRIER, OF EYRIE, TEXAS.

PUMP.

SPECIFICATION forming part of Letters Patent No. 619,534, dated February 14, 1899.

Application filed April 19, 1898. Serial No. 678,104. (No model.)

To all whom it may concern:

Be it known that I, JAMES M. BERRIER, a citizen of the United States, residing at Eyrie, in the county of Ellis and State of Texas, have 5 invented certain new and useful Improvements in Pumps; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

My invention relates to that class of pumps 15 which may be operated by means of steam or other power applied to a plunger-rod or piston-rod, and has reference particularly to the cylinder and valves of the pump.

It consists in a cylinder and piston by which 20 the fluid is drawn and forced in a continuous stream and in valves therefor, all of new and novel form and combination and arrangement of the several elements, whereby I provide a simple, effective, durable, and economical 25 pump, as will be more fully described hereinafter and claimed.

My object is to provide a pump which may be cheaply and conveniently constructed by the use of only such tools and facilities as are 30 found in small or isolated shops and which may also be readily repaired by as simple means.

My aim is to particularly improve the parts which usually in other pumps cause considerable 35 trouble and delays when parts have to be repaired or renewed, and this is accomplished in my invention, which is of such construction that ordinary non-expert attendants may repair it.

Referring to the drawings, in which like 40 letters of reference designate the same parts in the different views, Figure 1 represents a side elevation of a pump constructed in accordance with my invention; Fig. 2, an end elevation; Fig. 3, a front view of the piston; Fig. 4, a vertical central sectional view of the piston; Fig. 5, a front view of the packing-expanding devices applied to the piston; Fig. 6, a view of the inside surface of the piston 45 follower-plate; Fig. 7, a front or inside view of the piston-head; Fig. 8, a front view of the piston follower-plate; Fig. 9, an elevation of

the expanding ring; Fig. 10, an elevation of the packing-expander, and Fig. 11 a side view of a section of the expanding ring.

The cylinder A may be cast and, if desired, have a brass or copper lining and has a straight central bore. It is well adapted to be made of a piece of pipe or tubing without special tools and has at each end a flange a, which 55 may be either cast integrally or otherwise secured. Suitable legs b b or a stand is secured to the cylinder by suitable means. Each end of the cylinder is closed by a suitable head secured thereto by suitable bolts, the head A² 60 having a packing-box B² and packing-nut B³, through which the piston-rod B' works, and both heads A' and A² have a suitable port-opening, to which is connected a port-pipe A³, either cast integrally with the head or formed 65 of a pipe nipple and elbow, each of these having a union C for readily disconnecting when it is desired to remove a cylinder-head. To each union is connected a suitable line of pipe, in which are arranged four ordinary check-valves, so disposed that two valves shall be at 70 each side of the inlet or suction and discharge pipes, thus operating with one end of the cylinder, while two valves are similarly situated 75 to operate with the opposite end of the cylinder, this arrangement being shown in the drawings, in which d designates pipe-nipples of suitable length, e designates elbows, and f designates T's. The valves are designated as 80 D E F G, the first two being connected to a T h, to which the suction or well pipe S is connected, and the two latter being connected to a T i, to which the discharge-pipe k is connected. In connecting the yoke-like arrangement of pipes and valves some of the 85 parts may have right and left hand screw-threads, or unions may be suitably interposed, as desired, to render a connection practicable. The valves and pipe and fittings may be conveniently obtained in the open market. 90 The course of the fluid or water is indicated by the arrows upon the elbows, and the checks are set with their tops l upward, as is usual, and so that the fluid shall enter each one and pass through the valve-opening from the bottom, as indicated by dotted lines upon each 95 valve.

The piston B is so constructed that it may be easily packed and kept in close contact

with the cylinder without undue friction and is particularly adapted to have its packing quickly expanded when necessary without requiring the insertion of new packing. The 5 head-plate *m* is forced upon or welded to the rod *B'* and at its inner face has two recesses *N* to receive dowel-pins *u*, protruding from the rear side of the sections of the expanding ring *L*, so that the latter cannot rotate. The 10 ring *L* is made in sections having lapped ends *v w*, and outside of this is placed soft packing *K*, of hemp or other suitable material. Each of the sections has a swelled portion or lug *L'*. The expander *M* is in the form of a 15 collar bored to fit over the piston-rod between the plates *m* and *n* and is revoluble thereon. It has lugs *M'*, having eccentric-shaped faces, which are in contact with the swelled faces *L'*, so that when rotated in one direction the 20 ring *L* may contract, and an opposite rotative movement will expand the ring. Protruding from the front side of the expander is a pin *t*, to which is connected the eye of the bolt *R*, the pin and bolt working in a recess *J* in the 25 inner face of the follower-plate *n*. The latter has a slot *I*, in which a threaded nut *T*, working upon the threaded end of the bolt *R*, also works, being accessible by a wrench for adjustment through the slot, the latter being 30 covered by a removable plate *P*, secured by suitable screws to prevent fluid entering the piston when in use. The outer end of the rod *B'* is slightly reduced in diameter to form a shoulder against which the follower *n*, having 35 a hole *O*, is forced by the nut *H*, which is provided with screw-threads, as is the end of the rod *B'*. Thus the plate *n* is prevented from rotating on the rod. A movement of the nut *T* causes a rotation of the expander 40 *M*, and thus expands or contracts the ring *L*, according to the direction of movement.

In operation when the piston *B* is moving from the head *A'* to *A²* fluid will enter the cylinder through valve *D*, the valves *E* and *F* being closed while the fluid is being forced 45 from the opposite side of the piston through valve *G*. When the piston moves in the opposite direction, the fluid is forced out through valve *F*, valve *D* being closed, and fluid enters the opposite end of cylinder through valve *E*, check *G* being also closed.

I am aware that the valves and pipe-fittings are not in themselves new, and I do not so claim them; but I am not aware that such a 55 combination has been used whereby a pump

may be constructed from such readily-attainable parts as are embodied in my invention and so well adapted for being quickly renewed at isolated places when worn out.

It is immaterial what power is applied, as 60 the rod *B'* may be continued into a steam-cylinder or to any lever power device.

Having thus described my invention, what I claim, and desire to secure by Letters Patent, is—

1. In a pump, the combination of the cylinder *A* having a circular bore of uniform diameter therethrough and provided with the supporting-legs, the heads secured to the ends of said cylinder, the piston working in said cylinder and having the connecting-rod working through one of said heads, the elbow connected to the outer side of each of said heads, the unions connected to said elbows adjacent to said heads, the elbow *e* connected to each 70 of said unions, the *T f* connected to each of said elbows *e e*, the check-valves *D E* connected at one end to said *T*'s and at their opposite inlet ends to the suction-pipe, the check-valves *F G*, connected at their inlet ends to said *T*'s 80 and at their opposite outlet ends to the discharge-pipe, and the intermediate elbows and nipples, substantially as shown and described.

2. In a pump, the combination with the cylinder and piston-rod, of the piston consisting 85 of the plate *m* secured to said rod and having the recesses *N* in the inner face thereof, the plate *n* secured to the extremity of said piston-rod in proximity to said plate *m* and having the recess *J* in the inner face thereof, the sectional expanding ring *L* provided with the projections *L'* and interposed between said plates, the flexible packing *K* around said ring, the dowels *u* on said ring and engaging said recesses *N*, the expander *M* interposed between 95 said plates and within said ring and revoluble on said piston-rod and provided with the lugs engaging the projections on said ring, the pin projecting from the side of said expander and the adjusting bolt and nut connecting said 100 pin, said bolt working in said recess *J* and said nut working in a slot *I* in said plate *n*, substantially as shown and described.

In testimony whereof I affix my signature in presence of two witnesses.

JAMES M. BERRIER.
